UNITED STATES PATENT OFFICE.

JOSEPH W. WEISS, OF BALTIMORE, MARYLAND.

COLLAPSIBLE HAT-PACKAGE.

1,109,722.

Specification of Letters Patent.

Patented Sept. 8, 1914.

Application filed August 13, 1913. Serial No. 784,491.

To all whom it may concern:

Be it known that I, JOSEPH W. WEISS, a citizen of the United States of America, residing at the city of Baltimore, State of Maryland, have invented certain new and useful Improvements in Collapsible Hat-Packages, of which the following is a specification.

This invention relates to a package for hats consisting of a box together with hat spacing and positioning means.

The object of the invention is to reduce the cost of packing straw and other stiff hats by reducing the cost of shipping the boxes and hence their cost at the hat factory. The boxes are bulky and fragile and this fact is taken into account by the transportation companies with the result that the rate for shipment is correspondingly high.

For the purpose of reducing the cost of shipping, I provide a package consisting of a collapsible box together with spacing and positioning means for hats, every element of which is either flat or capable of being folded to a flat condition so that the whole may be packed in the minimum of space and will in fact occupy no more room than would the paper from which it is made.

While the box is essentially a collapsible box intended to be delivered in collapsed condition and set up by the shipper of hats, it may also be permanently set up by the box manufacturer and delivered by him in this condition to the local trade where the cost of transportation is comparatively low, and while the collapsible feature is an important element, the package which is herein described has, independently of this feature, the important advantage of being absolutely rigid and supporting the hats so that they cannot be injured either by contact with each other or with the box walls and this effect is enhanced by the use of corrugated paper for the box walls as this material forms an effective cushion for the hats if by any chance they should come in contact with the box walls. At the same time, the box is so designed that it may be produced with the minimum expense of labor and the maximum of economy as to material.

In the accompanying drawings I have illustrated a box embodying the features of my device in the preferred form. However, these features and combinations of details

are capable of being widely varied within the scope of the invention.

Figure 1 is a perspective view of the body of the box with the cover and bottom removed, the latter being shown slightly spaced from the box but otherwise in their operative relation. Fig. 2 is a vertical central section taken through the box showing the spacing and positioning members and the hats themselves in elevation. Fig. 3 is a plan of my collapsible hat spacer and 65 positioning member. Fig. 4 is a vertical central section through the positioning member showing the hat in operative relation thereto. Fig. 5 shows the spacing and positioning members, the parts being separated 70 ready to be collapsed. Fig. 6 shows the spacer in collapsed condition. Fig. 7 shows the body of the box collapsed.

The package consists of a box having its side walls 1 in the form of a collapsible cylinder or a polyhedron approaching the cylindrical in form, closed at the top and bottom by means of removable cover and bottom pieces 10 and 11 of the shape of the cross section of the box and having a rim or 75 flange 12 at right angles to the body of the cover and bottom pieces and adapted to inclose the edge portions of the side walls of the polyhedron at the end to which the particular member is applied. As shown, the 80 box is octagonal in form and of sufficient length to hold a plurality of hats, preferably a half dozen to each box, placed one on top of the other so that the hats are arranged in a single column, and of cross section 85 slightly greater in dimensions than the brims 2 of the hats 3 to be packed. The package also includes positioning and spacing members 4, consisting of a flat positioning member 5 and a cylindrical spacing 90 member 6. The positioning member is in the form of a sheet of pasteboard or the like, equal in form and dimensions to the corresponding dimensions of the cross section of the box opening and centrally apertured, the 100 aperture being slightly greater in dimensions than the cross section of the crown of a hat of the kind to be packed, and having projecting inwardly from the sides of the opening one or more tongues 7, preferably 105 two on opposite sides of the opening.

The cylindrical or spacing member 6 is in the form of a sheet of paste-board or the

like, which may be somewhat lighter in weight than the material forming the positioning member 5. This spacing member may be formed of a band of width somewhat exceeding twice the height of the crowns of the hats to be packed, joined at its ends to form an oval ring or cylinder 6, of sufficient size to receive the hat crowns. The spacing member is slotted at 8 at points corresponding to the position of the tongues 7 and intermediately of the width of the band so that the spacing member or cylinder 6 may be inserted within the aperture in the positioning member 5, and held by the tongues 7, the latter projecting through the slots 8 in the spacing member. The tongues 7 projecting through the slots also bear against the hats as shown in Figs. 3 and 4 engaging the lateral walls of the crowns and preventing displacement and vibration of the hats during transportation, thus eliminating a certain amount of wear.

It will be apparent that the spacing and positioning member 4 may be conveniently collapsed and packed in a space hardly greater than would be occupied by so much raw paper, the spacing member 6 being removed from engagement with the positioning member 5 and collapsed as shown in Fig. 6. Also the cover and bottom members 10 and 11 are removable, or rather when the box is made, the bottom is not fastened unless the box is intended for local delivery, but the tube which forms the body 1 is collapsed as shown in Fig. 7 and the cover, bottom, side walls and spacing and positioning members are all packed in flat form. The package as shown in Fig. 2, includes not only spacing and positioning members 4, but other such members 4', to be used at the top and bottom of the package. These have a shorter cylindrical or spacing member 6' than have the intermediate members 4, but are otherwise similar in that they consist of a positioning member 5' having tongues engaging slots in the band which forms the spacing member 6', but the latter incloses the crown of a single hat only and serves to space it from the top or bottom of the box as indicated in the drawing.

The hats when packed as shown in Fig. 2, placed in pairs, brim to brim and crown to crown, forming a single column of the length of the box, the crowns are inclosed by spacing members 6, 6', the larger cylinders 6 inclosing the pairs of juxtaposed crowns and the shorter members 6', the single end crowns. Thus the crowns are held out of contact with each other. With each spacing member, there is a co-operating positioning member 5 which serves to hold all the hats engaged by that spacing member in the center of the box.

With each hat being held centrally of the box by a positioning member 5 and having

its crown protected and held out of contact with any adjacent body, either the crown of the next hat or the top or bottom of the box, by the spacing members 6 or 6', the hats are as effectively protected from injury as they can well be when packed in any receptacle which is sufficiently light and cheap to be manufactured and shipped without prohibitive expense. The efficiency of the protection afforded the hats is increased by constructing the box of corrugated paper, which, should either the brim or crown of the hat come into contact with the box wall by indentation of the latter or displacement of the hat, acts as a cushion and protects the hat from injury even in such emergency, and the cost of the package is greatly decreased by the fact that every portion of it can be collapsed and the whole of it packed in the space ordinarily occupied by the same quantity of raw paper so that the expense of delivering it at the hat factory is reduced to the minimum.

I have thus described specifically a single embodiment of my invention in order that its nature and operation may be clearly understood. However, the specific terms herein are used in their descriptive rather than in their limiting sense and the scope of the invention is defined in the claims.

I claim—

1. A spacing and positioning member for hats, the spacing member consisting of a flat plate apertured in the form of the crown of the hat and having inwardly projecting tongues on the edges of the aperture, and the positioning member consisting of a cylinder within the aperture, slotted to receive the tongues, the cylinder being of a length exceeding twice the height of a hat crown.

2. A collapsible hat package consisting of a box having a collapsible tubular body of polygonal cross section, a correspondingly polygonal cover and bottom, each having an upright rim to inclose the end edges of the body, and spacing and positioning members within the box, the positioning members consisting each of a flat plate of dimensions to substantially fit the inside of the box, each positioning member being centrally apertured in the form of the cross section of the hat crowns and having inwardly projecting tongues on the edges of the aperture, the spacing members consisting each of a flexible band joined at its ends to form a ring or cylinder, slotted to receive the tongues, each cylinder being placed inside the aperture of a corresponding positioning member, the tongues of the positioning member entering the slots of the spacing member, the hats being placed in a single column, crown to crown and brim to brim, the adjacent crowns being inclosed each in a single spacing member of a length exceeding the height of the two crowns so that the tops of the crowns

are spaced apart, and the end crowns being inclosed in a single spacing member of reduced length slightly exceeding the height of the crown so that the crowns are held out of contact with the box and with each other, each spacing member being inclosed within a positioning member which engages the side walls of the box and keeps the edges of the

brims out of contact with the side walls of the box.

10

Signed by me at Baltimore State of Maryland this 29th day of July 1913.

JOSEPH W. WEISS.
